CLAIM

The ornamental design for a magnetic-ink printed character reader, as shown and described.

DESCRIPTION

FIG. 1 is a perspective view of the magnetic-ink printed character reader showing the new design;

FIG. 2 is a front view thereof;

FIG. 3 is a rear view thereof;

FIG. 4 is a left side view thereof;

FIG. 5 is a right side view thereof;

FIG. 6 is a plan view thereof;

FIG. 7 is a bottom view thereof;

FIG. 8 is a reference perspective view thereof showing an opening state of a tray; and,

FIG. 9 is a reference plan view thereof showing an opening state of a tray.

The broken lines represent portions of the magnetic-ink printed character reader that form no part of the claimed design.
